CLAIM

The ornamental design for a glass slider, as shown and described.

DESCRIPTION

FIG. 1 illustrates a perspective view of a glass slider in a first configuration according to the present disclosure, wherein a window of the glass slider is in an open position;

FIG. 2 illustrates a right elevation view of the glass slider of FIG. 1;

FIG. 3 illustrates a left elevation view of the glass slider of FIG. 1;

FIG. 4 illustrates a front elevation view of the glass slider of FIG. 1;

FIG. 5 illustrates a rear elevation view of the glass slider of FIG. 1;

FIG. 6 illustrates a top plan view of the glass slider of FIG. 1;

FIG. 7 illustrates a bottom plan view of the glass slider of FIG. 1;

FIG. 8 illustrates a perspective view of the glass slider of FIG. 1 in a second configuration, wherein the window of the glass slider is in a closed position;

FIG. 9 illustrates a right elevation view of the glass slider of FIG. 8; and,

FIG. 10 illustrates a left elevation view of the glass slider of FIG. 8.

The broken lines illustrate portions of the glass slider that form no part of the claimed design.

1 Claim, 8 Drawing Sheets
